DESIGN FOR A DRESS

Murray White, Brookline, Mass.

Application March 25, 1940, Serial No. 91,216

Term of patent 3½ years

To all whom it may concern:

Be it known that I, Murray White, a citizen of the United States of America, residing in Brookline, and State of Massachusetts, have invented a new, original, and ornamental Design for a Dress, of which the following is a specification, reference being had to the accompanying drawing, forming part thereof, wherein,

I claim:

The ornamental design for a dress, substantially as shown.

MURRAY WHITE.
